UNITED STATES PATENT OFFICE

110,378

DESIGN FOR A WOVEN TEXTILE FABRIC

John L. Walther, New York, N. Y.

Application March 18, 1938, Serial No. 75,911

Term of patent 3½ years

To all whom it may concern:

Be it known that I, John L. Walther, a citizen of the United States of America, residing in the city of New York, county of New York, and State of New York, have invented a new, original, and ornamental Design for a Woven Textile Fabric, of which the following is a specification, reference being had to the accompanying drawing, forming part thereof.

The drawing is a plan view of a woven textile

fabric showing my new design. The design embodies the full width of the fabric comprising relatively closely woven chevrons separated by bands of looser woven horizontal, nubby threads, each chevron having a thin loosely woven stripe thereon as shown.

I claim:

The ornamental design for a woven textile fabric, substantially as shown and described.

JOHN L. WALThER.
